CLAIM

The ornamental design for a footwear tread, as shown and described.

DESCRIPTION

FIG. 1 is a perspective top left view of the footwear tread of the present invention;

FIG. 2 is a top view thereof;

FIG. 3 is a left side view thereof;

FIG. 4 is a right side view thereof;

FIG. 5 is a front view thereof;

FIG. 6 is a rear view thereof;

FIG. 7 is a section view thereof taken along lines 7-7 of FIG. 2; and,

FIG. 8 is a perspective view thereof, illustrating the footwear tread positioned on a piece of footwear.

The broken away symbols in the drawings at the perimeter and bottom edges indicate that any portion of the article beyond what is shown forms no part of the claimed design. The broken lines depict environmental structure in the form of footwear, a footwear outsole, and other footwear treads that form no part of the claimed design. Additionally, the broken lines in the FIG. 2 view depict the location of the cross-section of the FIG. 7 view and also form no part of the claimed design.
